UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

DESIGN FOR AN ELECTRIC-CONDUIT FITTING.

52,628.

Specification for Design.

Patented Nov. 12, 1918.

Application filed July 15, 1918. Serial No. 245,121. Term of patent 14 years.

To all whom it may concern:

Be it known that I, CARL H. BISSELL, a citizen of the United States, residing at Syracuse, in the county of Onondaga and State of New York, have invented a new, original, and ornamental Design for an Electric-Conduit Fitting, of which the following is a specification, reference being had to the accompanying drawing, forming a part hereof.

In the drawing, Figure 1 is a plan view of my design for electric conduit fitting.

Figs. 2 and 3 are opposite end elevations thereof.

This ornamental design for electric conduit fitting comprises a body having substantially flat rectangular top and bottom faces and substantially cylindrical rounding end faces merging into the top and bot-

tom faces at the narrower ends of said top and bottom faces and end pieces, the upper and lower outer surfaces of which merge into the top and bottom faces at the longer sides of said faces and the end surfaces of which are a continuation of the rounding faces of the body; said end face having on the front sides projecting annular faces located centrally thereof.

I claim:

The ornamental design for an electric conduit fitting, substantially as shown and described.

In testimony whereof, I have hereunto signed my name, at Syracuse, in the county of Onondaga, and State of New York, this 3rd day of July, 1918.

CARL H. BISSELL.
